CLAIM

The ornamental design for a solar table, as shown and described.

DESCRIPTION

FIG. 1 is a top, front perspective view of a solar table showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is bottom, rear perspective view of the solar table shown in FIG. 1.

The broken lines in the drawings depict portions of the solar table that form no part of the claimed design.
